UNITED STATES PATENT OFFICE.

EBEN F. WILDE, OF ATTLEBORO, MASSACHUSETTS, ASSIGNOR TO THE BAER & WILDE COMPANY, OF ATTLEBORO, MASSACHUSETTS.

SEPARABLE CUFF BUTTON.

Application filed June 10, 1925. Serial No. 36,159.

To all whom it may concern:

Be it known that I, EBEN F. WILDE, a citizen of the United States, residing at Attleboro, in the county of Bristol and State 5 of Massachusetts, have invented new and useful Improvements in Separable Cuff Buttons, of which the following is a specification.

This invention relates to certain new and 10 useful improvements in separable cuff buttons and the primary object thereof is to provide an improved structure of the male and female members, which enables the parts to be easily and quickly assembled so as to 15 afford an economical and efficient construction.

The invention further aims to provide a 20 construction that is applicable both to the male and female members, excepting of course the cooperating heads or faces there- 25 of.

In the drawings:—

Figure 1 is a central longitudinal sectional view through the assembled button, 25 and

Figure 2 is a section on line 2—2 of Figure 1.

In proceeding in accordance with the present invention, the members are formed of 30 outer heads composed of bases 1 of cup- shape and in which filler and strengthening or reinforcing disks 2 are placed.

A ring-like member 3 having a right angular circular flange 4 is placed in the 35 cupped base 1 and the rim of the latter then spun over onto the margin of ring 3. The shank forming member 4' having flanged circular ends 5 and 6 is then fitted with its flange 5 disposed in the flange 4 of the ring, 40 whereupon the flange 4 is spun over onto the circular end 5 of the shank-forming member. The parts as thus far constructed and assembled may be used for either male 45 or female members of the button. In the instance of the male member an inner head 7 of dished or cup-form is provided and which is centrally perforated to receive the head 8 of a button 9, the base 10 of which latter and the head 7 seat on the flanged 50 end 6 of the shank-forming member. The

rim 7' of the head 7 encircles the periphery of the flanged end 6 and is spun thereover.

In the instance of the female member, an inner head 11 of dished or cup form is provided and which is also centrally perforated 55 and has a sleeve-socket 12 to receive the head 8 of the male member. The sleeve 12 is diametrically slotted at 13 to receive the arms 14 on the free ends of a spring member 15. The rim of the head 11 is likewise spun over into engagement with the flanged end 6 of the shank-forming member.

From the foregoing it will be apparent 60 that the buttons may be easily and quickly assembled without the use of solder and by 65 simple spinning operations affording a rigid and substantial construction.

Having thus described my invention what I claim as new and desire to secure by Letters Patent is:—

1. In a button, a cupped base, a ring on the base having a substantially right angular flange, the rim of the base being spun over the ring, and a shank having a flanged end, which extends outwardly from the 75 shank and the periphery of which abuts the flange of the ring, the free edge of the flange of the ring being spun inwardly onto the flange of the shank.

2. In a button, a cupped base, a ring on the base having a substantially right angular flange, the rim of the base being spun over the ring, a shank having a flanged end, which extends outwardly from the shank and the periphery of which abuts the flange of the ring, the free edge of the flange of the ring being spun inwardly onto the flange of the shank, a male element having a head and an outwardly extending dished base, the other end of the shank being flanged outwardly and dished to receive the dished base of the element, and a dished member perforated to receive the head therethrough and seated against the outer face of the base and having its free edge spun over the 95 dished flange of the shank to clamp the base of the male element against said dished flange of the shank.

3. In a button, a base, a shank carried thereby and having a flanged dished end, a 100

male element having a head and an out- of the shank to clamp the base of the male
wardly extending dished base, received in element against said dished flange of the
the dished flange of the shank base, and a shank.

dished member perforated to receive the In testimony whereof I have signed my
head therethrough and seated against the name to this specification.

outer face of the base of the head and hav-
ing its free edge spun over the dished flange

10
EBEN F. WILDE.
